(57) **CLAIM**

The ornamental design for a phone grip, as shown and described.

DESCRIPTION

FIG. 1 is a perspective view of a phone grip; FIG. 2 is a front elevational view with the rear, left side and right side elevational views being mirror images thereof; FIG. 3 is a top plan view thereof; FIG. 4 is a bottom plan view thereof; FIG. 5 is a front elevation view in the contracted position; FIG. 6 is a perspective view illustrating the device in use; and, FIG. 7 is a side elevation view illustrating the device in use. The broken lines in FIG. 4 depict portions of the article that form no part of the claimed design. The broken lines showing a hand and mobile device in FIGS. 6 and 7 depict environment that forms no part of the claimed design.

1 Claim, 7 Drawing Sheets
